UNITED STATES PATENT OFFICE.

DAVID KLINE, OF AKRON, OHIO, ASSIGNOR OF TWO-THIRDS TO AUGUSTUS D. POWER AND EDWARD A. STOUFFER, OF SAME PLACE.

OIL-BURNER FOR BOILERS, FURNACES, &c.

SPECIFICATION forming part of Letters Patent No. 469,211, dated February 16, 1892.

Application filed January 23, 1891. Serial No. 378,781. (No model.)

To all whom it may concern:

Be it known that I, DAVID KLINE, of Akron, in the county of Summit and State of Ohio, have invented certain new and useful Improvements in Oil-Burners for Boilers, Furnaces, &c.; and I do hereby declare the following to be a full, clear, and exact description of the invention, such as will enable others skilled in the art to which it pertains to make and use the same.

My invention relates to oil-burners for use in connection with furnaces for forging, brass-melting, and similar purposes; and it consists in certain novel features of construction and combinations of parts, as will be hereinafter described, and pointed out in the claims.

In the drawings, Figure 1 is an isometric view showing my feeder or burner as detached from the furnace; Fig. 2, the same with its top section lifted to show the interior construction of the upper chamber; Fig. 3, the same with the top and middle sections lifted to show the construction of the lower chamber. Fig. 4 is a plan view of my device with the upper section removed, showing the arrangement of the diverging directors and their relation with the oil-jet and air-blast. Fig. 5 shows my device in longitudinal vertical section taken through its central portion.

As illustrated in the drawings, my device is preferably constructed in three sections A, B, and C, which when assembled and bolted together present substantially the appearance indicated in Figs. 1 and 5.

As shown in Fig. 5, the roof offered by the section A slants downward toward the mouth or outlet, affording a chamber above the section B, say, of an inch in height, and gradually diminishing toward the mouth until the

space constituting the upper opening of the mouth—*i. e.*, the outlet between the sections A and B—is preferably, say, three thirty-seconds of an inch in dimension. I do not give these measurements as constituting a feature of my invention to which I propose to limit myself. I have in practice found these proportions to operate well; but in this respect my device may be varied without any departure from my invention.

Upon the upper face of the section B are

located diverging ribs D E. The ribs D, I preferably make to converge at a point in front of the oil-inlet F. The ribs E, located between the ribs D, are made of a height to fill or substantially fill the space between the floor and roof of the chamber between sections A and B and are made tapering to correspond with the longitudinal shape of said chamber. The arrangement of the ribs D E is such that the air as it is driven into the entrance G is made to evenly spread out into a fan-shaped body, and thus it escapes through the constricted mouth of the device into the furnace.

F is the oil-inlet, which is in any manner suitably connected with an oil-supply reservoir, and the oil is fed into the burner either by hydrostatic pressure or by means of a suitable pump.

Upon the under side of the section B are formed a number of diverging ribs E', corresponding substantially with the ribs E, already described, and these ribs operate to evenly spread and distribute the air passing through the lower chamber of the feeder, which is between the sections B and C, and which chamber, like that between A and B, tapers toward its mouth and has a restricted outlet. The oil is admitted only to the upper chamber, where it is caught by the air-blast and sent forward into the furnace. No oil is admitted to the lower chamber, through which air only is passed.

The entrance end G is in any effective way connected with a suitable fan or blower for producing the required air-blast, and the oil-supply pipe should be provided with a valve or cock for properly regulating the amount of oil fed to the burner.

The operation is as follows: The air is received at G, and, entering both the upper and lower chambers of the burner, is forced out through their constricted mouths into the furnace. The oil as it is fed into the upper chamber through the inlet F is instantly converted into a spray, which, mingling with the air, is spread out into a flat fan-shaped body and thus sent into the furnace and burned.

What I claim is—

1. An oil-burner comprising a series of fan-

shaped sections constructed to be secured together to form oil and air passages between them, these passages open at both ends, and an oil-supply pipe entering the oil-passage between its open ends, substantially as set forth.

2. An oil-burner comprising a series of fan-shaped sections constructed to be secured together, whereby air and oil passages are formed between them, an oil-supply pipe leading into one chamber, and ribs extending from the

point where this pipe enters to the discharge end of the burner, substantially as set forth.

In testimony whereof I sign this specification, in the presence of two witnesses, this 20th day of December, 1890.

DAVID KLINE.
